UNITED STATES PATENT OFFICE.

JOSEPH H. JOHNSON, OF BLISSVILLE, ARKANSAS.

LOG-BUOY.

1,163,931.

Specification of Letters Patent. Patented Dec. 14, 1915.

Application filed September 28, 1914. Serial No. 863,808.

To all whom it may concern:

Be it known that I, JOSEPH H. JOHNSON, a citizen of the United States, residing at Blissville, in the county of Drew and State 5 of Arkansas, have invented certain new and useful Improvements in Log-Buoys, of which the following is a specification.

The object of this invention is to provide means for causing logs of heavy wood 10 to float in water in which they would otherwise sink, and my invention comprises a float or buoy of improved construction which is provided with means for protecting it from injury by shocks caused by contact 15 of the logs which it supports with floating logs or other objects, and which is attached in an improved way to the logs which it sustains to form a raft.

The float is preferably made of sheet 20 metal and is preferably of cylindrical form closed watertight by heads at each end and strengthened at each end by a frame arranged within the heads. Near each end the cylinder is formed with a corrugation 25 providing an internal groove and an external rib which serve two purposes, viz., as seats for the strengthening frames and as a locking means for the buffer frames attached to the outside of the cylinder. These 30 buffer frames are preferably made of wood and surround the float near each end, being locked to the annular ribs thereon. Over the float and resting on the buffer frames is a plank on which rests cross poles to 35 which the logs to be supported are attached.

My invention is shown in the accompanying drawings, in which,

Figure 1 is a perspective view of a log buoy or float embodying my improvements 40 and shows also how said float is connected with the logs to be floated. Fig. 2 shows a transverse section on the line 2—2 of Fig. 1. Fig. 3 shows a longitudinal section on the line 3—3 of Fig. 1. Fig. 4 is a detail view 45 in perspective of a part of the buffer frame.

The float comprises a cylinder A made of sheet metal and formed near each end with an annular corrugation providing an internal groove a and an external rib a'. In 50 order to strengthen the cylinder I employ at each end a strengthening frame B consisting preferably of a wheel-like structure comprising a hub b, spokes b' and a rim b². Any other suitable frame may however be 55 employed. Two such frames are used, one near each end of the cylinder, and the rims

of these frames are seated in the grooves a, as clearly shown in Fig. 3. The ends of the cylinders are closed watertight by the heads a², a³. 60

In order to protect the float from injuries caused by shocks incident to the bumping of the supported logs against other logs or objects I provide the buffer frames C. Two such frames are used, one near each end of the cylinder. They surround the ribs a' and are locked thereto. Each frame comprises a body portion of rectangular form made up of wooden strips c' and corner pieces c² shaped as shown to connect with 70 the annular ribs a', being grooved at c³ to fit said ribs. The strips c' are also suitably grooved as shown to receive the ribs. One of the strips c' of each frame is made removable to enable the frame to be applied 75 to the float.

Fig. 1 shows the buffer frames in place and when so applied a firm connection is made between the frames and the float to prevent the buffer from displacement. 80

Over the float there is a plank D which rests on the top of the buffer frames and is prevented from slipping or being displaced by pegs d applied in the manner indicated. 85

Crosswise of the float there are poles E which rest on the plank D near each end thereof. Pegs e are applied to the plank on opposite sides of the poles to hold the latter in position. The cross poles extend a 90 considerable distance laterally on opposite sides of the plank in order that the logs X may be attached to them by means of the chains F which are attached to the dogs f driven into the logs. Each float may support several logs on each side, the floating capacity of the float being, of course, calculated and known to support or float a known weight or a known area of logs. In this 100 way heavy logs may be floated and carried down stream and a raft of large size may be constructed by suitably combining a number of floats and logs.

I have called the body A a cylinder but so far as part of my invention is concerned 105 said body may be of other shape.

I claim, as my invention:

1. A log buoy, comprising a floatable cylinder closed water-tight, buffer frames surrounding the cylinder near each end and 110 extending laterally from the top, bottom and sides of the cylinder, a plank resting

- on the buffer frames, poles resting on the plank and disposed cross-wise thereof, and means for connecting the poles to the logs to be floated.
5. 2. A log buoy or float, comprising a cylinder having near each end an annular internal groove and an annular external rib, heads applied watertight to the opposite ends of the cylinder, strengthening frames 10 within the cylinder engaging the grooves, and buffer frames surrounding the cylinder near each end and which are interlocked with the annular ribs thereof.
3. A log buoy or float, comprising a cyl-
- inder closed at each end watertight, 15 strengthening frames within the cylinder, buffer frames surrounding the cylinder, a plank resting on the buffer frames, poles resting on the plank and disposed cross-wise thereof, and means for connecting the 20 poles to the logs to be floated.

In testimony whereof, I have hereunto subscribed my name.

JOSEPH H. JOHNSON.
